Primary Examiner—Carmen H. Vales
Attorney, Agent, or Firm—Alexander, Unikel, Bloom, Zalewa & Tenenbaum, Ltd.

[57] CLAIM

The ornamental design for a display rack for water skis, substantially as shown.

DESCRIPTION

FIG. 1 is a perspective view of a display rack for water skis showing my new design;
FIG. 2 is a front elevational view thereof;
FIG. 3 is a right side elevational view thereof;
FIG. 4 is a top plan view thereof;
FIG. 5 is a bottom plan view thereof;
FIG. 6 is a rear elevational view thereof;
FIG. 7 is a side elevational view of another embodiment of the display rack for water skis shown in FIG. 1;
FIG. 8 is a top plan view thereof; and
FIG. 9 is a bottom plan view thereof.

UNITED STATES PATENT AND TRADEMARK OFFICE
CERTIFICATE OF CORRECTION

PATENT NO. : Des. 275,733

DATED : October 2, 1984

INVENTOR(S) : John Pardo

It is certified that error appears in the above-identified patent and that said Letters Patent is hereby corrected as shown below:

The "References Cited" portion on the face of the patent should include the following:

U.S. Des. 98,055	1/7/36	Conner
U.S. Des. 243,065	1/18/77	Picker D3/02
U.S. Des. 260,240	8/18/81	Carluccio D9/164
